UNITED STATES PATENT OFFICE.

JAMES F. BAKER, OF HUTCHINSON, KANSAS.

DESIGN FOR A CIGAR BAND.

60,122.

Specification for Design. Patented Jan. 3, 1922.

Application filed January 26, 1921. Serial No. 440,239. Term of patent 7 years.

To all whom it may concern:

Be it known that I, JAMES F. BAKER, a citizen of the United States, residing at Hutchinson, in the county of Reno and State of Kansas, have invented a new, original, and ornamental Design for Cigar Bands, of which the following is a specification, reference being had to the accompanying drawing, forming part thereof.

The figure is a plan view of the cigar band in opened position.

I claim:

The ornamental design for a cigar band, as shown.

JAMES F. BAKER.
